W. P. MURPHY.

CAR ROOF.

APPLICATION FILED NOV. 8, 1917.

1,259,464.

Patented Mar. 12, 1918.

Inventor:
Walter P. Murphy,
by himself,
his attorney.

UNITED STATES PATENT OFFICE.

WALTER P. MURPHY, OF NEW YORK, N. Y., ASSIGNOR TO P. H. MURPHY COMPANY, OF PARNASSUS, PENNSYLVANIA, A CORPORATION OF PENNSYLVANIA.

CAR-ROOF.

1,259,464.

Specification of Letters Patent. Patented Mar. 12, 1918.

Application filed November 8, 1917. Serial No. 200,864.

To all whom it may concern:

Be it known that I, WALTER P. MURPHY, a citizen of the United States, and a resident of the city of New York, in the county of New York and State of New York, have invented a new and useful Improvement in Car-Roofs, of which the following is a specification.

My invention relates to car roofs and more particularly to roofs of the type wherein corrugated metal sheets extend entirely across the car. In actual practice, the dimensions of the corrugations of such sheets do not run uniform but are liable to deviate considerably from the standard dimensions and thereby affect the fit of one sheet with another and with the space allotted to it in the design of the car.

The principal object of the present invention is to overcome the disadvantages due to deviations in the dimensions of the corrugations, to provide for proper securing of the sheets to the substructure in such manner as to permit movement of the sheets relative to each other, and to make proper provision for flashing and ventilating at the eaves. The invention consists in the construction and combination of parts hereinafter described and claimed.

In the accompanying drawing, which forms a part of this specification, and wherein like symbols refer to like parts wherever they occur,

Figure 1 is a plan view of a portion of a roof embodying my invention with parts broken away to expose the end portion of one of the carlines;

Fig. 2 is a cross-section on the line 2—2 of Fig. 1;

Fig. 3 is a detail perspective view of one of the slotted holding plates; and

Fig. 4 is a detail section through the end portion of a carline on the line 4—4 of Fig. 1.

The present roof comprises corrugated metal roof sheets 1 arranged transversely of the car and of sufficient length to extend from eaves to eaves with their corrugations extending crosswise of the car. The side margin of each sheet overlaps the side margin of the next adjacent sheet, the lap preferably extending two or three corrugations. Arranged on the side plate 2 of the car, at distances apart approximately equal to the

width of a roof sheet, are a number of plates 55 or castings 3 with elongated slots 4 therein adapted to receive the shanks of bolts 5. These slotted plates 3 are positioned under the corrugation of the overlapping sheet away from the lap, but next adjacent thereto; and this corrugation has a perforation, preferably in its crest, large enough for the shank of the bolt 5 to pass through. Surrounding the bolt and extending from the slotted plate to the under side of the corrugation is a thimble 6, whose upper surface conforms to the curvature of the corrugation and whose lower end rests on the slotted plate. Around the bolt hole said thimble has a raised portion which extends through 70 said corrugation so as to prevent the nut from being drawn down and clamping the sheet against the top of said thimble.

Where the lap of the roof sheets is located at a considerable distance from the carlines, 75 the form of slotted plate illustrated in Fig. 3 is suitable, and this form is especially desirable where a metal side plate of Z-shape is used, as illustrated in Fig. 2. In this form, the slotted plate comprises a body 80 portion which is riveted to the top of the side plate and has an upwardly offset portion extending outwardly beyond the vertical member of the side plate and containing the elongated slot 4, the outer edge of the 85 plate being within the outer limit of the lower flange of the side plate. Where the lap of the sheets occurs adjacent to the carline, it is desirable to form the elongated slot in the carline 7 itself, as illustrated in 90 Figs. 1 and 4. For this purpose, it is desirable to extend the end portion of the carline beyond the vertical member of the side plate so as to facilitate the placing of the bolts and insure that any leakage that might 95 occur around the bolt will run down on the outside of the car. When narrow sheets are used in connection with the wide spacing of the carlines, as illustrated in Fig. 1, the elongated slots may be used in the ends of 100 the carlines in conjunction with slotted plates intermediate the carlines.

Resting on top of the corrugated sheets and extending lengthwise of the car along the eaves is a metal retaining and flashing 105 strip 8 of angular section. One portion of this strip follows the pitch of the roof and is provided with bolt holes through which

pass the securing bolts 5. The inner edge 9 of this member is formed preferably into an inverted U-shape to stiffen the retaining strip. The outer portion of said strip 9 is bent vertically downward and has its lower edge 10 rebent inwardly to form a stiffening flange.

- It is noted that with the exception of the end sheet, the only fasteners extending through the sheets are the vertical bolts near one side margin of each sheet and that these bolts pass through the same corrugation, preferably the third corrugation from the side edge of the upper sheet at each joint. 10
- 15 In consequence of this arrangement, the sheets are firmly enough secured to the substructure but are free to accommodate themselves to any ordinary distortions of the car frame by reason of the fact that only one 20 of the sheets of each lap is secured near the lap. The function of the retaining and flashing strip is to hold the roof sheets down in proper relation to each other and to the substructure, and the downturned portion of 25 the retaining and flashing strip is intended to prevent the entrance of moisture at the eaves.

By reason of the elongation of the slot in the carlines and securing plates, ordinary 30 deviations in the dimensions of the corrugations can be fully accommodated, and in case of excessive distortions of the car frame, the sheets are free to move endwise of the car. So, too, the slot is made enough wider 35 than the shank of the bolt to permit a slight movement of the sheets crosswise of the car, such as occurs when the car goes out of square.

I claim the following as my invention:

- 40 1. A car roof comprising corrugated metal sheets extending crosswise of the car and lapped at their side margins, each sheet being secured to the substructure adjacent to one margin and being otherwise free.
- 45 2. A car roof comprising corrugated metal sheets extending crosswise of the car and lapped along their side margins, one of the roof sheets being secured to the substructure close to said lap and the other sheet being 50 free in the region of the lap, and a retaining strip for holding down said sheets.
3. A car roof comprising a substructure, retaining plates thereon having elongated slots therein, overlapping roof sheets on said

substructure, and fastening devices extending through said sheets and slots. 55

4. A car roof comprising a substructure having holes for fastening devices, corrugated roof sheets extending crosswise of said substructure and lapped along their margins, and fastening devices extending through one sheet only of each lap and movable in the holes of the substructure. 60

5. A car roof comprising corrugated metal sheets extending crosswise of the car and lapped along their side margins, one of the roof sheets of each lap being secured to the substructure close to said lap and the other sheet being free in the region of the lap, and a retaining strip for holding down said 70 sheets, said retaining strip comprising a portion above the sheets and a downturned portion beyond the ends of the sheets.

6. A car roof comprising a substructure having a Z-shaped side plate with its lower 75 flange extending outwardly, corrugated metal sheets extending crosswise of the car and lapped at their side margins, each sheet being secured to the substructure adjacent to one margin and being otherwise free, and 80 a retaining strip comprising a portion above the sheets and a downturned portion beyond the ends of the sheets but within the outer limit of the lower flange of the side plate.

7. A car roof comprising side plates, metal 85 sheets extending crosswise of the car and overlapping said plates, said sheets having raised stiffening members formed in their surface and at their overlapping side margins, and fastening devices extending 90 through the overlapping sheet adjacent each lap.

8. A car roof comprising metal sheets extending crosswise of the car and overlapping the top of the side walls thereof, said sheets 95 lapping each other at their side margins and having raised stiffening members formed therein, an angle-shaped retaining strip for holding down said sheets and fastening devices extending through the sheets 100 outside of their overlapped side margins for securing said retaining strip, said angle strip having one of its legs above the sheets and the other turned downward and inward beyond the ends of said sheets. 105

Signed at Chicago, Ill., this 2nd day of November, 1917.

WALTER P. MURPHY.
